UNITED STATES PATENT OFFICE.

JAMES H. RAND, OF NEWTON, MASSACHUSETTS.

INDEX.

1,284,772.

Specification of Letters Patent. Patented Nov. 12, 1918.

Application filed December 13, 1917. Serial No. 206,362.

To all whom it may concern:

Be it known that I, JAMES H. RAND, a citizen of the United States, and resident of Newton, in the county of Middlesex and 5 State of Massachusetts, have invented new and useful Improvements in Indexes, of which the following is a specification.

This invention relates to a card ledger or card index of the so-called visible type, 10 wherein a series of cards or sheets are supported in an upright frame in overlapped relation with their margins exposed to display names or other identifying subject matter. The invention has to do chiefly with the 15 holder for the cards or sheets, and the relation between the holder and the frame.

In the accompanying drawings which illustrate certain embodiments of the invention,

20 Figure 1 is a fragmentary view, in front elevation, of a part of a ledger or index embodying the invention;

Fig. 2 is a face view of one of the holders with the parts assembled in operative position;

Fig. 3 is a sectional view on line 3-3 of Fig. 2;

Fig. 4 is a face view of said holder showing one end of the hanger detached from 30 the rail;

Fig. 5 is a perspective view of said holder with a card or sheet mounted thereon;

Fig. 6 is a sectional view on line 6-6 of Fig. 1, and

Fig. 7 is a perspective view illustrating a modification.

The frame of the device, which may be of usual construction, comprises the body or back A made with inturned flanges or lips a 40 at its opposite edges to form inwardly facing channels for receiving the ends of the card or sheet holders. The frame is preferably made of sheet metal.

Each of the holders, which will be arranged one above another in the frame, comprises a bar or rail B preferably made of bristol board or paper board or some similar flexible, resilient material. The ends of the holder are inserted within the channels 50 of the frame by bending the central part thereof away from the frame, thereby shortening the distance between the ends, and thereafter allowing the holder to spring into flat position again with its ends in the guide channels. A hanger C, preferably made of metal wire or some other suitable flexible,

resilient material, extends lengthwise of the rail B and is secured to the rail in such manner that one end at least of the hanger is separable from the rail to facilitate applying 60 and removing the card or sheet supported thereby. The other end of the hanger may be permanently attached to the rail. As herein shown one end of the hanger C is bent over and passed through an aperture or 65 perforation b in the rail B and upset on the rear side as shown at c. The other end of the hanger C is bent over as shown at c to engage a socket, preferably consisting of a slot b' cut in the rail B and extending in- 70 ward from the end thereof. Thus the bent-over end c permanently secures that end of the hanger to the rail B, and also permits the hanger C to swing relative to the rail B on the pivotal connection formed by the aper- 75 ture b and the bent-over end of the hanger. The other end of the hanger c' is readily separable from the socket b' by merely springing the hanger and rail apart so that the bent-over end c' and the socket b' are dis- 80 engaged.

D represents a card or sheet with a fold at the top for engaging the hanger C. The card or sheet D may be readily applied to its holder or removed therefrom by disengaging 85 the ends of the rail and hanger and slipping the card endwise upon or off from the hanger.

It will be seen by reference to Figs. 1 and 6, that the bent-over end c' and socket b' 90 form separable attaching means for securing one end of the hanger to the rail, and that when the device is assembled and inserted in the frame with the end c' and socket b' positioned within one of the channels formed 95 by the flange a of the frame, said separable attaching members connecting the hanger and the bar are held and locked in engagement by the channel of the frame.

In the modification shown in Fig. 7 the 100 rail B is similar to that shown in the other figures save that it has a slot or socket member b' formed in each end, and the hanger C has a bent-over projection at each end similar to the bent-over end c' shown in the 105 other figures. With this construction the rail and hanger are separable at both ends instead of only at one end and said separable attaching means are held in engagement at both ends by the opposed channels of the 110 frame, when the device is assembled.

By making the hanger separable from the

rail at one or both ends it is much easier to apply or remove the card or sheet than if the hanger were permanently fastened at both ends, in which case it would be necessary to 5 tuck the card or one leaf or fold of the card between the rail and hanger. With the present construction it is also possible to use a card or sheet which is even wider than the distance between the ends of the rail by 10 cutting away the corners of the card or sheet at the fold as illustrated in the drawings. Such card wider than the distance between the ends of the hanger could not be inserted without crumpling the card unless one or 15 both ends of the hanger were detachable.

I claim:

1. A holder for indexes of the class described comprising a rail and a hanger extending lengthwise of the rail, at least one 20 end of the hanger being separable from the rail, and both rail and hanger being made of flexible resilient material whereby insertion of the holder in an index frame can be effected by bending both the hanger and 25 the rail.

2. A holder comprising a rail of flexible resilient fibrous material, such as paper-board, and a hanger of flexible resilient wire extending lengthwise of the rail, at least 30 one end of the hanger being separable from the rail.

3. A holder comprising a rail having a slot extending inward from at least one end, and a wire hanger mounted on and extending 35 lengthwise of the rail, one end at least of the hanger being bent over to engage said slot.

4. A holder comprising a rail having a slot extending inward from one end, and a wire hanger extending lengthwise of the rail, one end of the hanger being bent over 40 separably to engage said slot, and the other end of the hanger being permanently secured to the rail.

5. A frame having inwardly facing channels, and a holder mounted therein comprising a rail, a hanger, and separable attaching means by which one end at least of the hanger is detachably secured to the rail, 45 said separable attaching means being held in engagement by one of the channels of the frame.

6. A frame having inwardly facing channels, and a holder mounted therein comprising a rail, a hanger, and separable attaching means by which one end at least of the hanger is detachably secured to the rail, 50 said separable attaching means being positioned within one of the channels of the frame and thereby locked in engagement.

7. A frame having inwardly facing channels, and a holder mounted therein comprising a rail, a hanger, and separable attaching means by which one end at least of the hanger is detachably secured to the rail, 55 comprising a socket formed at the end of the hanger and a projection on the end of the hanger to engage the socket, said socket and projection being positioned within one of the channels of the frame and thereby locked 60 in engagement with each other.

Signed by me at North Tonawanda, New York, this eighth day of December, 1917.

JAMES H. RAND.
